RADIO RECEIVER GAIN CONTROL

Adolf Westerveld, Eindhoven, Netherlands, assignor to Hartford National Bank and Trust Company, Hartford, Conn., as trustee

Application July 30, 1947, Serial No. 764,754
In the Netherlands March 5, 1943

Section 1, Public Law 690, August 8, 1946
Patent expires March 5, 1963

5 Claims. (Cl. 250—20)

1

The invention relates to a radio-receiver with negative feedback in the low-frequency part thereof, which receiver comprises means of controlling the amplification.

In the construction of simple radio-receivers it is important to effectuate the control of the amplification with the aid of a number of components which is as small as possible. The present invention affords means of providing a simple radio-receiver with a very effective volume control.

According to the invention, use is made in the above-mentioned radio-receiver both of a high-frequency volume control brought about with the aid of a potentiometer and of a low-frequency volume control brought about by means of a variable negative feedback, the control of the negative feedback and the high-frequency volume control being effected by means of the same potentiometer.

The potentiometer is preferably connected to the voltage to be fed back and, moreover, it is included, at least partly, in the aerial circuit. In this case the regulating contact of the potentiometer is connected, as the case may be, with the interposition of suitable impedances, both to the control grid of a high-frequency amplifying tube or a frequency-changer and to the control grid of a low-frequency amplifying tube.

A simple radio-receiver with a particularly effective control of the amplification may be obtained if the said receiver is constructed as a superheterodyne reflex-receiver wherein both the intermediate-frequency oscillations and the low-frequency oscillations derived therefrom after amplification and detection are amplified in the same discharge system, in which automatic control of the amplification is utilized.

The invention will be explained more fully with reference to the accompanying drawing, which represents the diagram of a superheterodyne reflex-receiver wherein the control of the amplification is effected in accordance with the invention.

The aerial is connected, through the intermediary of a coupling condenser 1, to a potentiometer which consists of two resistances 2 and 3 and which is connected to the secondary terminals of a loudspeaker transformer 4, from which the voltage to be fed back negatively is taken. The regulating contact of the potentiometer is connected, on the one hand, through the intermediary of an input oscillatory circuit 5 which is tuned to the high-frequency oscillations to be received, to the control grid of a heptode system 6 which serves to change the

2

frequency and, on the other hand, through the intermediary of a resistance 7 and an intermediate-frequency circuit which will be described hereinafter, to the control grid of a triode system 8 which operates in reflex-connection. The systems 8 and 6 form together a triode-heptode.

By displacing the regulating contact of the potentiometer 3, both the high-frequency voltage on the control grid of the heptode system 6 and the degree of low-frequency negative feedback of the triode 8 are regulated. In the highest position of the contact the high-frequency voltage has the highest value and the negative feedback is switched off; in the lowest position the high-frequency voltage has the smallest value whereas the degree of the negative feedback is at its maximum. The two controls consequently support one another; this is important in connection with the automatic volume-control utilized for the triode 8, for this automatic volume-control, which is necessary in order to avoid overloading of the triode, has the tendency of decreasing the effect of the control of the high-frequency voltage so that, in order to ensure a sufficiently uniform volume control, an additional control in the low-frequency portion is desirable. The combination of the automatic volume control in the reflex-tube and of the previously described high-frequency and low-frequency volume-controls results in a particularly effective control of the amplification.

The heptode 6 acts at the same time as an oscillator and to that end it is connected in three-point connection to an oscillator circuit 9. In the anode circuit is also incorporated the first circuit of an intermediate-frequency band-pass filter 10 the second circuit of which forms part of the control grid circuit of the triode 8. The intermediate-frequency oscillations produced in the anode circuit of the heptode 6 are consequently taken to the control grid of the triode; the amplified oscillations are taken from an intermediate-frequency circuit 11, which is inductively coupled to the anode circuit of the triode 8 and, for the purpose of rectification, they are supplied to the interconnected diodes of a duo-diode-pentode 12. The rectified voltage is taken from a potentiometer system consisting of two resistances 13 and 14 and is supplied to the control grid of the triode 8, the direct-current component of the rectified voltage being also transmitted and an automatic control of the amplification of the triode 8 being obtained. The stability of the triode circuit is promoted owing to the presence of a neutrodyne condenser 15 connected

between the anode circuit and the control grid circuit.

The amplified low-frequency oscillations which are set up across a resistance 16 in the anode circuit of the triode 8 are supplied through a coupling condenser 17 to the control grid of the pentode portion of the discharge tube 12. In the anode circuit of the pentode is included the primary winding of the previously mentioned loud-speaker transformer 4. The mid-point of the secondary winding of this transformer is earthed.

The tuning of the circuits 5 and 9 to the signal to be received is preferably effected by varying the self-inductance of this circuit with the aid of slidable iron cores.

What I claim is:

1. A receiver circuit arrangement for the reception of carrier signals having a modulation frequency component, comprising a carrier frequency stage having an input circuit, a modulation frequency stage coupled to said carrier frequency stage and having input and output circuits, a potentiometer having a movable tapping, means to derive a negative feedback voltage proportional to said modulation component from the output circuit of said modulation frequency stage and to apply said voltage to the ends of said potentiometer, means to apply said signals to one end of said potentiometer, and means to couple the tapping of said potentiometer to the input circuit of said carrier frequency stage and to the input circuit of said modulation frequency stage.

2. A superheterodyne receiver circuit arrangement for the reception of carrier signals having a modulation frequency component, comprising a carrier frequency mixing stage having an input circuit, a modulation frequency amplification stage coupled to said carrier frequency stage and having input and output circuits, a potentiometer having a movable tapping, means to derive a negative feedback voltage proportional to said modulation component from the output circuit of said modulation frequency stage and to apply said voltage to the ends of said potentiometer, means to apply said signals to one end of said potentiometer, and means to couple the tapping of said potentiometer to the input circuit of said carrier frequency stage and to the input circuit of said modulation frequency stage.

3. A reflex receiver circuit arrangement for the reception of carrier signals having a modulation frequency component, comprising a carrier frequency stage having an input circuit, an amplification stage coupled to said carrier frequency stage, a detector stage coupled to said amplification stage, a modulation frequency stage coupled to said amplification stage and having an output circuit, means to apply a portion of the output of said detector stage to said amplification stage, a potentiometer having a movable tapping, means to derive a negative feedback voltage proportional to said modulation component from the output circuit of said modulation frequency stage and to apply said voltage to the ends of said potentiometer.

ometer, means to apply signals to one end of said potentiometer, and means to couple the tapping of said potentiometer to the input circuit of said carrier frequency stage and to said amplification stage.

4. A reflex receiver circuit arrangement for the reception of carrier signals having a modulation frequency component, comprising a carrier frequency stage having an input circuit, an amplification stage coupled to said carrier frequency stage, a detector stage coupled to said amplification stage, means to derive an output potential from said detector stage, said potential having a first component proportional to said modulation component and a second component constituting an automatic volume control voltage, means to apply said potential to said amplification stage, a modulation frequency stage coupled to said amplification stage and having an output circuit, a potentiometer having a movable tapping, means to derive a negative feedback voltage proportional to said modulation component from the output circuit of said modulation frequency stage and to apply said negative feedback voltage to the ends of said potentiometer, means to apply said signals to one end of said potentiometer, and means to couple the tapping of said potentiometer to the input circuit of said carrier frequency stage and to said amplification stage.

15. A receiver circuit arrangement for the reception of carrier signals having a modulation frequency component, comprising a carrier frequency stage having an input circuit, a modulation frequency stage coupled to said carrier frequency stage and having input and output circuits, first and second resistive elements, one of said resistive elements having a movable tapping, means to connect together one end of each of said resistive elements to define a junction, means to derive a negative feedback voltage proportional to said modulation component from the output circuit of said modulation frequency stage and to apply said voltage to the other ends of said resistive elements, means to apply said signals to said junction, and means to couple said tapping to the input circuit of said carrier frequency stage and to the input circuit of said modulation frequency stage.

35. A receiver circuit arrangement for the reception of carrier signals having a modulation frequency component, comprising a carrier frequency stage having an input circuit, a modulation frequency stage coupled to said carrier frequency stage and having input and output circuits, first and second resistive elements, one of said resistive elements having a movable tapping, means to connect together one end of each of said resistive elements to define a junction, means to derive a negative feedback voltage proportional to said modulation component from the output circuit of said modulation frequency stage and to apply said voltage to the other ends of said resistive elements, means to apply said signals to said junction, and means to couple said tapping to the input circuit of said carrier frequency stage and to the input circuit of said modulation frequency stage.
